UNITED STATES PATENT OFFICE.

ALBERT KILBORN, OF MIDDLE BRIGHTON, VICTORIA, AUSTRALIA.

ELASTIC-FLUID MOTOR FOR MILKING APPARATUS.

1,032,220.

Specification of Letters Patent. Patented July 9, 1912.

Application filed January 12, 1911. Serial No. 602,212.

To all whom it may concern:

Be it known that I, ALBERT KILBORN, a subject of the King of Great Britain, residing at "Bondi," New Street, Middle Brighton, in the State of Victoria, Commonwealth of Australia, engineer, have invented Improvements in Elastic-Fluid Motors for Milking Apparatus, of which the following is a specification.

10 This invention relates to improvements in elastic fluid motor mechanisms and more especially to mechanisms of this type as employed in connection with pneumatic milking machines, and the primary object of the 15 invention is to provide an improved and efficient mechanism of this character which is composed of two parts and is simple in construction.

To these and other ends, the invention 20 consists in certain improvements, combinations and arrangements of parts, all as will be hereinafter more fully described, the novel features being pointed out particularly in the claims at the end of the specification.

In the accompanying drawing:—Figure 1 represents a vertical section of a pneumatic motor mechanism embodying the present invention and adapted for use in 30 connection with milking machines; Fig. 2 represents an axial section through a motor mechanism of somewhat modified form, the cylinders and pistons being arranged in tandem or axial alinement; and Fig. 3 is a 35 sectional view of another modified form of the invention wherein the cylinders for the respective pistons are constructed separately and their ports are connected by appropriate piping.

40 Similar parts are designated by the same reference characters in the several views.

In that form of the invention shown in Fig. 1, the mechanism comprises generally a base 19 having a flange 19^a adapted to seat 45 upon and form a fluid-tight connection with the rim of a bucket or receptacle, a gasket being interposed as usual to insure a tight fit. The base 19 is formed with a pair of openings 1 which extend through the base; 50 a pair of cylinder casings are mounted on the upper side of the base, one of these cylinder casings having a relatively large cylinder P which forms the cylinder chamber P', and a relatively smaller cylinder P² 55 which forms the smaller cylinder chamber 15. The other casing embodies a relatively large cylinder S forming the relatively large cylinder chamber S' and it also embodies a relatively smaller cylinder S² which forms a relatively smaller cylinder chamber 16. I term the cylinder P a "primary" cylinder 60 and the cylinder S the "secondary" cylinder, the heads of these two cylinders being preferably removable but normally held in position by a clamp member P³, a threaded standard P⁴ the lower end of which is attached to the base 19, and a nut P⁵ which is threaded upon the upper end of the standard and bears upon the clamping member P³. A piston 2 reciprocates and has a fluid-tight fit within the primary cylinder P, this piston 2 being connected to or formed integrally with a piston valve 3 which reciprocates and has a fluid-tight fit within the valve cylinder P², the valve 3 having a single cylindrical head which is connected to the piston 2 by a stem of reduced diameter. A piston 4 reciprocates and has a fluid-tight fit within the secondary cylinder S and this piston is connected to or formed integrally with a piston valve 5 which reciprocates and has a fluid-tight fit within the corresponding valve cylinder S², the valve 5 embodying a pair of axially spaced heads which are connected to one another and to the piston 4 by stems of reduced diameter. The cylinder P² containing the piston valve 3 has a port 6 formed in the wall thereof at a point intermediate its length and this port 6 is connected by a pipe or conduit 9 to a port 11 which communicates with the upper end of the secondary cylinder chamber S'. The rate of flow of fluid through the port 11 may be throttled or controlled by a suitable throttle valve 11^a having a spring as shown to frictionally hold it in different adjusted positions, and in this way the frequency of the pulsations due to the reciprocating motions of the pistons may be regulated. The cylinder S² also has a port 7 formed in its wall and at a point intermediate its length, the port 7 communicating through the pipe or conduit 10 with a port 12 which communicates with the top of the primary cylinder chamber P'. A vent to the atmosphere 13 is provided in the wall of the cylinder P² at a point above the port 6 of this cylinder, and this cylinder P² is also formed with a suitable number of circumferentially spaced ports 17 which communicate with a nipple 18, the latter being adapted to be attached by hose as usual to the milking de-

vices. The cylinder S^2 is also formed with vents 14 leading to the atmosphere, one of these vents extending axially through the lower head of the secondary cylinder S and the other vent extending laterally through the wall of the valve cylinder S^2 adjacent to the upper end thereof, and the wall of the cylinder S^2 is also formed with a passage 8 which leads from the under side of the base 19 into the cylinder chamber 16 at a point intermediate the length thereof. A pipe or tube 20 is attached to the base 19 and may be connected by a hose or other suitable means to a source of fluid pressure supply or, assuming the apparatus to be used in connection with milking mechanism, this pipe or tube 20 will be connected to a vacuum pump whereby vacuum pressure will be maintained beneath the base 19.

In operating the mechanism just described in connection with milking apparatus, the base of the mechanism is placed upon a bucket or other receptacle and a partial vacuum is maintained in the bucket or receptacle and at the under side of the base by an exhaust pump attached to the pipe or tube 20, it being understood that the nipple or tube 18 is connected by hose or other suitable means to the milking devices.

While the pistons occupy the positions shown in Fig. 1, the vacuum pressure acting upon the relatively smaller pistons 3 and 5 will tend to draw both pistons downwardly. However, at this time the passage 8 leading from the under side of the base 19 will cause air to be exhausted from the upper side of the piston 2 through the port 12, the connecting pipe 10, port 7 and the chamber 16, and owing to the relatively larger area of the piston 2, the force acting on the smaller valve piston 3 will be overcome and the pistons 2 and 3 will rise. Upward motion of the pistons 2 and 3 will cause the piston 3 to uncover the ports 6 and 17. Uncovering of the port 17 creates a vacuum pressure in the tube 18 connected to the milking devices and uncovering of the port 6 causes air to be exhausted from the upper side of the secondary piston 4 through the port 11 and the connecting pipe 9. The secondary piston 4 together with the valve pistons 5 will then rise owing to the greater area offered by the upper side of the piston 4 to the vacuum pressure as compared with the area of the relatively smaller valve piston 5, and rising of the secondary piston 4 and the valve piston 5 will establish communication between the port 7 which communicates with the upper side of the primary piston 2 and the atmosphere vent 14 in the wall of the valve cylinder S^2 , air from the atmosphere being thereby permitted to flow to the upper side of the primary piston 2 and the vacuum pressure to which the under side of the valve piston 3 is subject will draw the pistons 2,

and 3 downwardly, the valve piston 3 then establishing communication between the port 6 and the atmosphere vent 13 to permit atmospheric air to flow into the space above the secondary piston 4 and enabling the vacuum pressure at the under side of the valve piston 5 to draw the secondary piston 4 and the valve pistons 5 downwardly. The downward motion of the valve piston 3 also establishes communication between the port 17 and the atmosphere vent 13, thereby permitting air at atmospheric pressure to flow to the milking devices connected to the pipe or nipple 18. This cycle of operations is repeated in the order named.

In that embodiment of the invention shown in Fig. 2, the primary and secondary cylinders P and S are arranged in axial alinement or in tandem fashion, and the relatively smaller valve cylinders P^2 and S^2 are interposed between the primary and secondary cylinders and these two cylinders are in alinement and formed as a continuation of the other. The primary and secondary pistons 2 and 4 operate within the respective cylinders and the piston valves 3^a and 5^a operate in the respective valve cylinders P^2 and S^2 . In this embodiment of the invention, the nipple 18 communicates with a port 17 formed in one wall of the valve cylinder P^2 , this nipple being connected as usual by hose to the milking devices and a tube or nipple 20 communicates with a port 1^a formed at the point where the valve cylinders P^2 and S^2 join, it being understood that the nipple or tube 20 is connected by a hose or otherwise to a vacuum pump. The valve cylinders P^2 and S^2 are provided as before with atmosphere vents 13 and 14 and also with the ports 6 and 7, the port 6 of the valve cylinder P^2 being connected by a pipe 9 to the port 11 at the outer end of the secondary cylinder chamber S' and the port 7 in the wall of the valve cylinder S^2 is connected by a pipe 10 to the port 12 at the outer end of the primary cylinder chamber P' . In this instance the piston valve 3^a is formed with two transverse ports and an axial port 15, and the piston valve 5^a is formed with an angular port 8^a which leads from the inner end thereof and extends laterally to control the port 7. To enable the motor mechanism to be used for power purposes, the primary piston 2 is provided with a piston rod 21 which extends through a stuffing box 22 at the outer end of the primary cylinder. In this embodiment of the invention, the vacuum to which the port 1^a is subject will cause air to be exhausted through the port 8^a in the piston 5^a, port 7, pipe 10 and port 12, a vacuum pressure being created in the primary cylinder chamber P' at the right hand side of the primary piston 2 and this piston together with the piston valve 3^a will move toward the right.

Such movement of the pistons 2 and 3^a will cause the ports 6 and 17 to be uncovered, air being exhausted then through the hose connected to the nipple 18 and 5 also through the port 6, pipe 9, and port 11, thus creating a vacuum pressure in the cylinder chamber S' at the left hand side of the secondary piston 4, the latter piston together with the piston valve 5^a being 10 thereby drawn to the left and establishing communication between the port 16^a of the piston valve 5^a and the atmosphere vent 14 and the port 7, air at atmospheric pressure then flowing through the ports 14, 15 16^a and 7, through the pipe 10 and port 12, and entering the primary piston chamber P', the primary piston 2 and its piston valve 3^a being then drawn toward the left due to the vacuum pressure acting upon the piston 20 valve 3^a. Movement of the primary piston 2 and its piston valve 3^a to the left establishes communication between the atmosphere vent 13 and the port 15 in the piston valve 3^a, a portion of the atmospheric air 25 flowing through the port 17 and the hose leading to the milking devices, such hose being connected to the nipple 18, and a portion of the air at atmospheric pressure entering the vent 13 will flow through the port 6, the pipe 9 and the port 11 into the secondary cylinder chamber S', permitting the secondary piston 4 and the piston valve 5^a to move toward the right, this cycle of 30 operations being repeated during operation of 35 the apparatus.

In that embodiment of the invention shown in Fig. 3, the casing forming the secondary cylinder S with its cylinder chamber S' and the relatively smaller valve cylinder S² is formed separately from the casing P^o. A secondary piston 4 and a corresponding piston valve 5^a operate in the cylinders S and S² respectively, and in this instance, the piston valve 5^a is formed with 40 a pair of ports 8^a and 16^a, the port 8^a controlling the flow of fluid through the port 7, pipe 10, and port 12, while the port 16^a controls communication between the atmosphere vent 14 and either the port 7 or the 45 port 7^a, the latter port communicating by a pipe 10^a with a port 12^a formed in the opposite end of the primary cylinder P^o, the construction and mode of operation of the valve 5^a in this instance being similar to the 5 valve 5^a in Fig. 2. The bottom of the cylinder S² is closed and has a port 1 to which the motive fluid supply pipe 20 is connected. A pipe 3^a also leads from the bottom of the cylinder S² into the wall of the primary cylinder P^o at a point between the ports 12 and 12^a. The port 11 at the upper or outer end of the secondary cylinder S is connected by the pipe 9 to the port 6 which is formed in the wall of the primary cylinder 5 P^o adjacent to the port 3^a. An atmosphere

vent 13 is also formed in the wall of the primary cylinder P^o next to the port 6. In this embodiment of the invention, a combined piston and valve 3^b is employed which reciprocates in the primary cylinder P^o, this 70 piston and valve being formed with a circumferential groove or port 15 which serves to alternately establish communication between the port 6 and the atmosphere vent 13 and the pipe 3^a. The port or passage 15 75 in the piston and valve 3^b also communicates with a port 17 to which the nipple or pipe 18 is connected, this nipple or pipe 18 serving for the attachment of the hose connected to the milking devices. In this embodiment of the invention, the motor mechanism is also adapted to be used for power purposes, the member 3^b being provided for this purpose with a piston rod 21 which extends through a stuffing box 22 on the forward end of the cylinder P^o. The operation 80 of this embodiment of the invention is as follows: Assuming the parts to initially occupy the position shown in Fig. 3 and also assuming that the pipe 20 is connected to 85 a source of fluid pressure supply, the port 8^a in the valve piston 5^a registering with the port 7 will cause motive fluid to flow through these ports and through the pipe 10 and port 12 into the space at the right 90 hand side or in rear of the member 3^b of the primary motor, the space at the opposite side of the member 3^b communicating with the atmosphere for exhaust purposes 95 through the vent 14, ports 16^a, 7^a, pipe 10^a 100 and port 12^a. The piston member 3^b will make a stroke toward the left. Movement of the member 3^b toward the left will establish communication between the atmosphere vent 13 and the port 6, these ports being 105 bridged at this time by the port 15 to the piston member 3^b. Air above the piston 4 is then free to exhaust to the atmosphere through the port 11, pipe 9 and ports 6, 13 and 13. Fluid pressure at the under side 110 of the valve piston 5^a will then move this piston together with the piston 4 upwardly and this shifting of the piston 5^a will cause the port 16^a thereof to establish communication between the atmosphere vent 14 and the port 7 so that air pressure at the right 115 hand side of the piston member 3^b will be exhausted through the port 12, pipe 10, and ports 7, 16 and 14. Upward movement of the valve piston 5^a also uncovers the port 7^a 120 and permits motive fluid to flow through the port 7^a, pipe 10^a and port 12^a, causing the piston member 3^b to produce a stroke toward the right. This movement of the piston member 3^b toward the right 125 causes the port 15 of this piston member to establish communication between the port 6 and the pipe 3^a, permitting motive fluid to flow through these passages, through the pipe 9 and port 11 and to act upon the 130

upper side of the relatively large piston 4, causing the latter and the valve piston 5^a to produce a downward stroke, thus returning the elements to the initial position, this cycle of operations being repeated as long as the apparatus continues to operate.

I claim as my invention:

1. In an elastic fluid motor, the combination of a cylinder having a piston and valve member operative therein, a second cylinder of differential areas having a piston and a piston valve of differential areas operative in unison therein, means for constantly subjecting said piston valve to the action of the motive fluid to move the same in one direction, and means controlled by said piston and valve member for alternately subjecting said second mentioned piston to the action of the motive fluid to move the same in an opposite direction and in opposition to the action of the motive fluid on said piston valve.

2. In an elastic fluid motor, the combination of a cylinder having a piston and valve member operative therein, a second cylinder of differential areas having a piston and a piston valve of differential areas operative in unison therein, means for constantly subjecting said piston valve to the action of the motive fluid to move the same in one direction, and means controlled by said piston valve for intermittently subjecting said member to the action of the motive fluid to move said member in one direction.

3. In an elastic fluid motor, the combination of a secondary cylinder having differential areas and provided with a piston of large diameter directly connected with a piston valve of smaller diameter, a primary cylinder having differential areas and provided with a piston of large diameter directly connected with a piston valve of smaller diameter, means to maintain the smaller areas of said cylinders always in direct communication with the elastic motive fluid, the smaller areas of said cylinders being provided with ports located intermediate of their lengths, and a passage connected to each of said ports for alternately delivering fluid and air against the respective piston of the other cylinder.

4. In an elastic fluid motor, the combination of a secondary cylinder having differential areas and provided with a piston of large diameter directly connected with a piston valve of smaller diameter, a primary cylinder provided with a piston and valve member, means for subjecting said piston valve in the secondary cylinder to the action of the elastic motive fluid, and means controlled by said piston valve for delivering fluid and air alternately against said piston and valve member.

5. In an elastic fluid motor, the combination of a cylinder having differential areas

provided with a piston in the larger area directly connected with a piston valve in the smaller area, another cylinder provided with a piston and valve member, means for subjecting one end of said valve member to the action of the elastic motive fluid, and means controlled respectively by said valve and valve member for subjecting the opposite end of said member and said piston to the action of the motive fluid.

6. In an elastic fluid motor, the combination of primary and secondary cylinders, each having differential diameters, means for maintaining the smaller areas of said cylinders in direct communication with a source of elastic motive fluid, a piston in the primary cylinder of large diameter directly connected with a smaller piston valve in the smaller area thereof, a piston in the secondary cylinder of large diameter directly connected with a smaller piston valve in the smaller area, means connecting the large area of the piston in the secondary cylinder alternately with the motive fluid and the atmosphere under the control of the piston valve of the primary cylinder, and means connecting the large area of the piston in the primary cylinder alternately with the motive fluid and atmosphere under the control of the piston valve of the secondary cylinder.

7. In an elastic fluid motor, the combination of primary and secondary cylinders, each having differential diameters, means for maintaining the smaller areas of said cylinders always in direct communication with a source of elastic motive fluid, a piston in the primary cylinder of large diameter directly connected with a piston valve in the smaller area thereof, the smaller area of the primary cylinder having an air port toward one end thereof and also a port at an intermediate point connected with the larger area of the secondary cylinder, both of said ports being controlled by said piston valve in the primary cylinder to alternately deliver fluid and air to said secondary cylinder, and a piston in the secondary cylinder of large diameter directly connected with a piston valve in the smaller area of the secondary cylinder, an air port being formed in the smaller area of the latter and toward one end thereof, a port being also formed toward the middle thereof and connected with the larger area of the primary cylinder, the piston valve of the secondary cylinder controlling said ports to alternately deliver fluid and air to the piston in the primary cylinder.

8. In milking apparatus, the combination of primary and secondary cylinders, each having differential diameters, the smaller areas of said cylinders being always in direct communication with a source of elastic motive fluid, a piston in the primary cylinder

inder of large diameter directly connected with a piston valve in the smaller area thereof, the latter having an air port formed therein toward one end and a motive fluid 5 port connected with the larger area of the secondary cylinder, said ports being controlled by said piston valve in the primary cylinder to alternately deliver fluid and air to the larger area of the secondary cylinder, 10 and a piston in the secondary cylinder of large diameter directly connected with a piston valve in the smaller area of the secondary cylinder, the latter having an air port open to the atmosphere, and a port 15 connected with the larger area of the primary cylinder, both of said ports in the secondary cylinder being controlled by said piston valve therein to alternately deliver fluid and air to the larger area of the primary cylinder, a port being 20 formed in the smaller area of the primary cylinder adapted to be connected to the teat cup tube and adapted to communicate alternately with the motive fluid and air under the control of the 25 piston valve of the primary cylinder.

9. In milking apparatus, the combination of primary and secondary cylinders, each having differential diameters, means for maintaining the smaller areas of said cylinders always in direct communication with an elastic motive fluid, a piston in the primary cylinder of large diameter directly

connected with a piston valve in the smaller area of the primary cylinder, the latter having an air port and a port connected with the larger area of the secondary cylinder, both of said ports being controlled by said piston valve in the primary cylinder to alternately deliver fluid and air to the piston in the secondary cylinder, and a piston 40 in the secondary cylinder of large diameter directly connected with a piston valve in the smaller area of the secondary cylinder, the latter having an air port and a port connected with the larger area of the primary cylinder, both of said ports in the secondary cylinder being controlled by said piston valve in the secondary cylinder to alternately deliver fluid and air to the larger area of the primary cylinder, a port being 45 also formed in the smaller area of the primary cylinder to communicate with the teat cup tube and adapted to intermittently communicate with the motive fluid under the control of the piston valve in the primary 50 cylinder.

In testimony whereof I have hereunto set my hand in presence of two subscribing witnesses.

ALBERT KILBORN.
